atty's.

UNITED STATES PATENT OFFICE.

GEORGE G. FLOYD, OF ST. LOUIS, MISSOURI, ASSIGNOR TO AMERICAN STEEL FOUNDRIES, OF ST. LOUIS, MISSOURI, A CORPORATION.

BOLSTER.

SPECIFICATION forming part of Letters Patent No. 732,403, dated June 30, 1903.

Application filed April 25, 1903. Serial No. 154,206. (No model.)

To all whom it may concern:

Be it known that I, GEORGE G. FLOYD, a citizen of the United States, residing in the city of St. Louis, in the State of Missouri, have 5 invented certain new and useful Improvements in Bolsters, of which the following is a full, clear, and exact description, reference being had to the accompanying drawings, forming part of this specification.

10 The object of my invention is to produce a body-bolster for railway-cars in a manner that will permit of its removal from the draft members without taking off the end sill or other parts of the rigging, the construction of 15 the bolster being such that it can be readily repaired when put back in position and when repaired will be of substantially the same strength and durability as when first put into use.

20 The invention consists in features of novelty hereinafter fully described, and pointed out in the claim.

Figure I is a side elevation of my improved bolster, the draft members and sills being 25 shown in vertical section. Fig. II is a top or plan view. Fig. III is a detail longitudinal section taken on line III III, Fig. I. Fig. IV is a vertical transverse section taken on line IV IV, Fig. I. Fig. V is a detail side view 30 showing the bolster in the condition it assumes after the draft members have been renewed.

Referring to the drawings, 1 represents the bolster, which I have shown as consisting of an upper chord 2, a lower chord 3, and a connecting-web 4. The lower chord is provided 35 with the usual side bearings 5 and center bearing 6.

7 represents the outside sills of the car-body, and 8 the inner sills. The outside sills 40 rest upon the ends 9 of the lower chord, and they are strengthened and supported by means of braces 10 connecting them to the upper chord.

11 represents the draft members, located 45 in openings 12 formed in the bolster. These draft members are bolted or riveted to flanges 13, that connect the upper and lower chords together and which are formed integral

therewith. It frequently happens that these draft members or sills have to be renewed, 50 and it is the object of my invention to so construct the bolster that this can be done without removing the ends sills or other parts of the draft-rigging. When this renewal work is to be done, I cut the upper chord on the 55 dotted lines A, Fig. I, and then by cutting off the heads of the rivets that connect the members to the flanges 13 the bolster can be removed in a downwardly direction to permit the removal of the draft members, and when 60 the draft members have been removed the bolster is placed back in position, after which a strap 14, Fig. V, is riveted or bolted to the upper chord, this strap extending across the openings 12, as shown. It is necessary to have 65 the openings as wide throughout their lengths as the widest part of the draft members in order that the bolster can be removed in a vertical direction after the parts A have been cut out. 70

A bolster thus made affords a convenience also in that if it should become broken or useless it can be removed without taking off the end sill and replaced by a new bolster of the same kind, the new bolster being first cut at 75 A to permit it to be placed in position, and when placed in position the strap 14 would be applied thereto. When the bolster has been thus repaired, it is of substantially the same strength and durability as when first 80 put into use. The work can be quickly done, and by thus forming the bolster it is necessary to remove it from its position when the draft members have to be renewed. 85

I claim as my invention—

A body-bolster for railway-cars having an upper chord and centrally-located flanges and having openings on each side of the flanges to receive the draft members; said openings being as wide throughout their length as the 90 width of the draft members, substantially as set forth.

GEORGE G. FLOYD.

In presence of—

E. S. KNIGHT,
BLANCHE HOGAN.
